UNITED STATES PATENT OFFICE.

WILLIS M. BAUM, OF SAUGUS, CALIFORNIA.

RAILROAD-CROSSING.

1,292,233.

Specification of Letters Patent. Patented Jan. 21, 1919.

Application filed February 13, 1918. Serial No. 216,983.

To all whom it may concern:

Be it known that I, WILLIS M. BAUM, a citizen of the United States, residing at Saugus, in the county of Los Angeles and 5 State of California, have invented a new and useful Railroad-Crossing, of which the following is a specification.

My invention relates to railroad crossings, in which the gap in the intersection of the 10 rails is closed in one direction, while gaps through the intersections of the rails in the other direction are open.

One object of this invention is to provide a shockless crossing.

15 Another object is to provide a noiseless crossing.

Another object is to provide plugs in the gaps in the intersection of the rails in a crossing for closing the gaps in the 20 intersections when desired.

Another object is to provide a cam below each of such plugs for shifting the plugs to a position closing the gaps in the intersection of rails or opening the gaps to allow 25 the passing of a train through the crossing without causing any shock to the train, or any noise while the train is passing through the crossing.

Another object is to provide proper operating means for such plugs and cams.

Other objects will appear from the following description and appended claims, as well as from the accompanying drawing, in which:—

35 Figure 1 is a detail side elevation of a plug in closing position in relation to the rails and the operating cam.

Fig. 2 is a top plan view of the railroad crossing showing the gaps in the pavement 40 of a street or place where such crossing is located.

Fig. 3 is a fragmentary detail side elevation of the operating means for operating the cams in my device.

45 Fig. 4 is a top plan view of the operating means of my device assembled.

Fig. 5 is a fragmentary detail section through the plugs and the cam in my device slightly modified, showing a connection 50 between the plugs and cams.

In Fig. 1, 6 designates the plug vertically slidably mounted in each intersection of the rails in a crossing, making eight plugs to a crossing of two rails crossing two other 55 rails. 7 designates the ends of two rails in a crossing, leaving a gap 8 to allow the

flanges of car wheels to pass crosswise over such rail. Eight such gaps are normally in one crossing, as will be easily understood from Fig. 2, where 9 designates the gaps in 60 the crossing in one direction, while 10 designates the gaps in the crossing in the direction crosswise to the first direction.

If a train is passing through the crossing in Fig. 2 in the direction from the rails 65 11 over the short rails 12 toward the rails 13, the gaps 10 naturally should be filled up to carry the car wheels over from the rails 11 to 12 and from 12 over to 13 without any shock or noise, and the gaps 9 should 70 naturally be open to allow the passage of the wheel flanges through the crossing in the indicated direction. A train or car passing in another direction from the rails 14 over the short rails 15 toward the rails 16, 75 or in opposite direction, naturally requires a closing of the gaps 9 and a free passage through the gaps 10, as will easily be understood.

I prefer to have the plugs 6 slidable for 80 vertical movement in such gaps, and for convenient operation of the plugs I prefer to have the cams 17 on the shafts 18, see Fig. 1. A quarter turn of the shaft 18 from the position illustrated in Fig. 1 to the position indicated in dotted lines at 19 causes the plugs 6 to drop down a suitable distance to allow the flanges of car wheels to pass over the rails or through the crossings. The cam standing in a position as illustrated 90 in Fig. 1 allows a car wheel to pass over the gap between the ends of the rails in a crossing as over a continuous rail.

In Fig. 4 a cam 17^b is provided on each end of the shafts 18^b, the cams on the opposite 95 shafts 18^b projecting upwardly, while the cams 17^a on the other two shafts 18^a project sidewardly, so that car wheels could pass in a direction over the rails 11 and 12 to 13 either way, having a free passage through the gaps 100 9 and a closed gap 10 for supporting wheels in this direction. For automatically operating the plugs suitable operating means are illustrated in Fig. 3, in which figure the shaft 18 is provided with arms or levers 20, 105 to which the connecting link 21 is pivotally connected. The end 22 of bar 23 is pivotally connected to the free end of the connecting link 21, it being pivotally supported at 24, and having a vertically disposed bar 25 connected to the free end 26. The upper end 27 of the bar 25 projects into the path of the

wheel flanges passing along the rails. To prevent a quick wear-out of the end 27 of the bar 25, a tread piece 28 is disposed over the bar 25, receiving the shock or pressure from the wheel flanges. The wheel 29 with the wheel flanges 30 indicated in dotted lines in Fig. 3 passing along a rail, naturally presses the tread piece 28 down, thereby transmitting such pressure to the bar 25, this causing the end 26 of the bar 23 to swing around the pivot support 24 to cause the end 22 to move in an upwardly direction, thereby turning the shaft 18, bringing the cam 17 to the position indicated in dotted lines at 19 in Fig. 15. 1. The operation of the cam in the described manner allows a dropping of the plug 6 alongside of that rail near which the tread 28 is located, while the plugs disposed so as to form a continuous tread in this same rail 20 remain in the top or closing position. In single crossings there will of course be such operating means for operating the shafts in either direction, while in double crossings there being four rails crossing four rails, it 25 will naturally require only one such operating means for each pair of rails. That means four operating means to a single crossing as well as four operating means to a double crossing.

30 For operating these crossings under the solenoid system the shafts 18^a and 18^b naturally will have other levers 31 for connecting the solenoids 32 and 33 as illustrated in Fig. 4. In this figure the solenoid 33 is shown in a position under operation, having caused the turning of spider 34, thereby turning two shafts with a cam projecting upwardly, while two shafts are turned bringing the cams projecting sidewardly, as explained above. An operation of the solenoid 32 causes a movement of the spider 34 in the opposite direction, so as to turn the shafts 18^a to a position to bring the cams 17^a to an upwardly-projecting position, while the shafts 18^b are turned so as to bring the cams 17^b to projecting sidewardly, as will easily be understood.

For operating this crossing under the plug system bars 35 are also connected to the levers 31 for turning the shafts 18^a and 18^b in a similar manner as described above.

Fig. 5 illustrates a detail construction by which the plugs 6 can be turned downwardly 55 out of the gap by the cam 18, the cam 18

being provided with a suitable recess 36 and the plug 17 being provided with suitable lips 37 slidably mounted in the recess 36 of the cams. Of course I do not want to limit myself to such minor details of construction, 60 as any other means can be easily adopted without departing from the principle of the invention, the main idea being to show that a sticking of the plugs in the gaps will not prevent an operation of the device. 65

Having thus described my invention, I claim:

1. In a railroad crossing of the class described, in combination with plugs disposed in the gaps in the intersections of the rails 70 in such crossing, of rotating cams disposed below the plugs for operating the plugs so as to slide vertically in the gaps.

2. In a railroad crossing of the class described, in combination with plugs disposed 75 in the gaps in the intersections of the rails in such crossing for vertically slidable movement, shafts disposed below the rails, and cams provided on the shafts below the plugs for operating the plugs in such vertical 80 movement, by the turning movement of the shaft and the cam.

3. In a railroad crossing of the class described, in combination with plugs disposed 85 in the gaps in the intersections of the rails in such crossing for vertically slidable movement, shafts disposed below the rails, cams provided on the shafts below the plugs, and operating means for operating the plugs in such vertical movement through the turning 90 of the cams on the shafts.

4. In a railroad crossing of the class described a plug in each of the gaps in the intersections of the rails in the crossing, a cam suitably disposed in relation to each of the 95 plugs for operating the plugs to the desired position in relation to the gaps in the crossing, operating means connected to each cam for automatically operating the cams when car wheels pass through the crossing, 100 and other operating means connected to the cams for manually operating the cams, all substantially as described.

In testimony whereof I hereunto affix my signature in the presence of two witnesses: 105

WILLIS M. BAUM.
